UNITED STATES PATENT OFFICE

HARRY L. BRADLEY, OF MILWAUKEE, WISCONSIN, ASSIGNOR OF ONE-HALF TO LYNDE
BRADLEY, OF MILWAUKEE, WISCONSIN

DESIGN FOR A SHOE HORN

Application filed March 5, 1931. Serial No. 38,940. Term of patent 14 years.

To all whom it may concern:

Be it known that I, HARRY L. BRADLEY, a citizen of the United States, residing at Milwaukee, in the county of Milwaukee and State of Wisconsin, have invented a new, original, and ornamental Design for Shoe Horn, of which the following is a specifica-

tion, reference being had to the accompanying drawings, forming part thereof.

The single figure is a perspective view of a shoe horn showing my design.

I claim:

The ornamental design for a shoe horn, as shown.

HARRY L. BRADLEY.
